PLANT IDENTIFYING MARKER

Henry U. Holzer, Hyde Park, Mass.

Application July 17, 1935, Serial No. 31,851

1 Claim. (CL. 40—10)

This invention relates to plant identifying markers for use in gardens and its object is to provide a marker comprising a post or support member provided with novel label-attaching means that securely hold a label against displacement and permit the ready removal and reinsertion of the same at will.

My invention will be described in connection with the accompanying drawing in which:

10 Fig. 1 is a vertical elevation of a plant identifying marker embodying my invention.

Fig. 2 is a fragmentary longitudinal section taken on the line 2—2 of Fig. 1.

15 Fig. 3 is a transverse section taken on the line 3—3 of Fig. 1.

Fig. 4 is an elevation partly in section of a modification.

Fig. 5 is a transverse section taken on the line 5—5 of Fig. 4.

20 Fig. 6 is an elevation of a further modification.

Fig. 7 is a fragmentary longitudinal section taken on the line 7—7 of Fig. 6.

Fig. 8 is a transverse section taken on the line 8—8 of Fig. 6.

25 Fig. 9 is a plan view of the label.

In the particular drawing selected for more fully disclosing my invention, 10 is a post or support member consisting of a flat metal strip having a central longitudinal rib 11 terminating a

30 short distance from the upper end of the member, such distance being equal approximately to the width of the label 13, which may be of cardboard, fibre, or other suitable material.

By cutting away the upper portion of the rib, a space

35 is provided for receiving the label, which in each

of the forms of my invention is secured between

two longitudinally spaced tongues integral with

the support member.

In the form shown in Fig. 1, the lower tongue

40 12 is formed by removing a short length of the

base portion of the rib, leaving an overhang, as

shown in Fig. 2. The upper tongue 14 is formed

by bending the upper end of the strip 10 back on

itself.

45 The two horizontal edges of the label are pro-

vided, respectively, with oppositely disposed in-

dentations 15, 16, for receiving the tongues afore-

said, whereby said label is securely held against

displacement.

50 In the modification illustrated in Fig. 4, the

upper end of the tube 20 is flattened, thereby forming two parallel plates 21, 21' equal in length approximately to the width of the label. The lower tongue 22 is struck out of the plate 21' by a suitable punch inserted through the opening 5 23 in the plate 21. The upper tongue 24 is formed by bending the end of the plate 21' back on itself.

In the modification shown in Fig. 6, the post or standard is a flat metallic strip 30 provided, as 10 in the case of the other two embodiments of my invention, with two longitudinally spaced tongues 31, 32, the tongue 31 being formed by bending the upper end of the strip back on itself, and the tongue 32 being formed from the strip by a striking-up punch.

In each of the embodiments of my invention the label preferably is formed with the indentations 15, 16, for receiving the longitudinally spaced tongues, however, the latter may be formed.

The label is readily inserted between the tongues by bending it longitudinally and placing one of the edges thereof against the support with its indentations under one of the tongues, and the other edge against the support immediately forward of the other tongue and then upon releasing it, the elasticity of the label will cause it to snap into position and be firmly held against displacement. Obviously by bending the label so as to bring one or both of the indentations out 30 of engagement with the tongues, said label may readily be removed from a given post in case it is desired to change labels, instead of going to the expense of using a different post.

Having thus described illustrative embodiments 35 of my invention, what I claim and desire to secure by Letters Patent is:

A plant identifying marker comprising a flat supporting member having a central longitudinal rib terminating short of the upper end thereof to afford a space for receiving a label, the base portion of said rib being removed near the upper end thereof to form a label-engaging tongue, a tongue integral with said support member at the upper end thereof, and a label secured between said tongues, said label having two oppositely disposed indentations for receiving said tongues.
